CLAIM

The ornamental design for a display device with an invoice tracker for a graphical user interface, as shown and described.

DESCRIPTION

FIG. 1 is a front view of a display device with an invoice tracker for a graphical user interface; and,
 FIG. 2 is a second embodiment thereof.

The elongated dashed lines between the circular features are ornamental and form part of the claimed design. The two outermost broken lines showing a display device and remaining broken lines showing elements of the graphical user interface illustrate portions of the article and do not form part of the claimed design.
